UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

RECEIVING DEVICE FOR ELECTRIC TRANSMISSION.

No. 833,224.

Specification of Letters Patent.

Patented Oct. 16, 1906.

Application filed March 25, 1905. Renewed April 4, 1906. Serial No. 309,886.

To all whom it may concern:

Be it known that I, ISIDOR KITSEE, of the city and county of Philadelphia, State of Pennsylvania, have invented certain new and useful Improvements in Receiving Devices for Electric Transmission, of which the following is a specification.

My invention relates to an improvement in receiving devices for electric transmission, and has more special reference to receiving instruments used on such lines where the resistance and capacity do not allow the direct employment of the usual sounders or other electromagnetic devices—as, for instance, on submarine cables, where now the well-known siphon-recorder is generally employed. The arrangement and working of this siphon-recorder is so well understood that it does not need further description here. It suffices to say that a finely-drawn glass tube immersed with one end in an ink-well and the other end in proximity to a moving paper is actuated by a coil suspended between a magnetic field, and a message is written on the paper in the form of curves representing the direction of the current, and as a dash is represented by a positive impulse and a dot by a negative impulse the apparently irregular line can easily be interpreted by the receiving operator. It is conceded by the officers in charge of such lines that to receive messages by sound would greatly benefit the service, leaving the record only for future reference, and it is the aim of my invention to make it possible to receive messages over lines, as above stated, with the aid of an electromagnetic device—such, for instance, as a sounder—and it is the further aim of my invention to combine my arrangement with a recording device, so that at one and the same time the message may be recorded and also read by the sound, and I have illustrated this my arrangement as combined with the siphon-recorder usually employed on submarine cables; but it is obvious that instead of a siphon-recorder any other recording instrument may be used in conjunction with my invention.

On long-distance lines—as, for instance, submarine cables—the received impulses are of such feeble character that it is well-nigh impossible to actuate therewith an electromagnetic device, such as a relay, in a manner

so as to make and break a local circuit containing the necessary translating devices, and this fact, combined with the moving of the zero, an action well understood by persons versed in the art, bars entirely the employment of any device whereby the moving parts shall make and break connection at stated intervals with stationary contacts. To overcome one of these objections, the so-called "moving of the zero," I have recourse to a method of telegraphing which is more particularly described in Letters Patent issued to me December 13, 1904, under Serial No. 777,259, which method is called "telegraphing with true reversals," and in this system of telegraphing with true reversals the zero position of instruments placed on submarine or other cables is substantially stationary. To overcome the other objection—that is, the well-known impossibility of making an electrical contact through the different incoming impulses—I have recourse to a method and arrangement as will hereinafter be more fully described, illustrated in the drawings, and more specially pointed out in the claims following the specification.

In the drawings, Figure 1 is a partial perspective and partial diagrammatic view embodying my invention. Fig. 2 is a plan view of part of the device employed by me.

A is the receiving instrument proper, here shown as the siphon-recorder usually employed in submarine cables. Of this device A' is the glass tube or siphon, and A² the paper whereon the received messages are recorded. So far the arrangement and parts of the device are the same as those already in use; but to carry out the purpose of my invention I provide the movable part of the recorder—in this case the glass siphon—with a piece of non-conducting material B, preferably a very thin piece of mica, and secure the same to the siphon with the aid of one of the well-known means—such, for instance, as a shellac or other cement.

In proximity to the moving siphon A' are placed the adjustable contact pair C and C' and the adjustable contact pair C² and C³, the contacts of the first pair supported by the piece D and the contacts of the second pair supported by the piece D', which supports are non-conducting. Each pair of contacts

are in practice arranged in a manner so as to allow a small air-space to exist between the extreme points of same.

In the drawings the air-space between contacts C and C' is designated as E and the air-space between the contacts C² and C³ is designated as E'.

G is an electromagnetic device—such, for instance, as a common sounder—provided with the two coils G' and G², wound around the common core G³. This electromagnetic device is also provided with the armature G⁴.

F is a source of current, here shown as a battery. The coils G' and G² of the electromagnet G are connected to this battery and the contact-points in the following manner: The positive pole of the battery is connected through wire 1 with the interposition of the impedance K with one of the contacts of each pair of contacts, here contact C and C². The contact C' of the first contact pair is connected through wire 2 with the upper terminal of coil G², the other terminal of this coil being connected through wire 3 with the upper terminal of the coil G', the other terminal of this coil G' being connected through wire 6 and wire 4 with the contact C³ of the second contact pair: The negative pole of the battery F is connected through wire 5 with wire 3—that is, with the wire connecting the two coils in opposition with each other. It is now supposed that the contacts of each of the contact pairs are in electrical connection with each other. The flow of the current therefore from the battery F would be as follows: positive pole of battery F, wire 1. Here the current will divide and part of same will go through contacts C and C', wire 2, coil G², wire 3, wire 5, back to the negative pole of the battery F. The other part of the current will flow through contacts C² and C³, wire 4, wire 6, coil G', wire 3, wire 5, back to the negative pole of battery F, and as it is supposed that the resistance of the circuit including the contact pair C and C' is equal to the resistance of the circuit including the contact pair C² and C³, and as the coils G' and G² are connected in opposition as to each other—that is, in a manner so that their magnetizing effect should be neutralized on the core G³—it is obvious that this core will remain neutral as long as the flow of the current remains undisturbed. The armature of such a device will remain inactive during this whole period. It is now supposed that the resistance of one or the other of the contact pairs is increased to a great extent. In such case the current will flow in inverse proportion to such resistance, and as the balance is disturbed and as a greater amount of current will flow through one coil than through the other the core G³ will be energized and the armature G⁴ will be actuated. In reality the contacts of each of the contact pairs are not in metallic connection, but are, as stated

above, so adjusted as to allow an air-space to exist between the extreme points of the two contacts of each pair. The flow of the current from the battery F will therefore be entirely interrupted, and if no other means is present to reduce the resistance of this air-space then the flow of the current will always remain interrupted. Now for the purpose of causing the current to flow through the coils G' and G² and for the purpose of reducing the resistance of the air-spaces E and E', I have recourse to the following arrangement: I connect one contact of each pair, here contacts C and C², with a source of alternating or interrupted current, the secondary of which I designate as H and the primary of which I designate as H'. I connect the other contacts of each pair, here C' and C³, with the same source H.

In the drawings the contacts C and C² are connected through wire 7 with interposition of condenser L with one terminal of the source H and the contact C' is connected through wires 8 and 9 with the other terminal of the source H and contact C³ is connected through wires 4 and 9 with the same terminal. We therefore have, first, a circuit including the direct source of current F connected with one pole in multiple arc to the contacts C and C² and with the other pole 95 and the interposition of the two coils G' and G² in multiple arc to the contacts C' and C³, and as an air-gap intervenes between the contacts of each pair the flow of this current is interrupted; second, a circuit including 100 the source of alternating or interrupted current H, connected also in multiple arc with one terminal to the contacts C and C² and with the other terminal to the contacts C' and C³, and as this alternating or interrupted 105 current is of an intensity strong enough to overcome the resistance of the air-gap this current will flow from the source H through wire 7, will divide (if the resistance of the two air-gaps is equal) equally between C 110 and C², and one part will flow through C, through air-gap E to C', wire 8, wire 9, back to the other terminal of H. The other part of the current will flow from contact C², through air-gap E', contact C³, wire 4, wire 9, 115 back to the source H. Through the flow of this current the resistance of both of the air-gaps will be reduced so as to present a path conducting enough for the flow of the direct current from the source F, and this current, 120 therefore, will flow from the positive pole of F, through wire 1, impedance K, will divide in equal portions, and one part will flow through contact C, air-gap E, contact C', wire 2, coil G², wire 3, and wire 5, back to the 125 negative pole of the source F. The other part of the current will flow through contact C², air-gap E', contact C³, wire 4, wire 6, coil G', wire 5, back to the negative pole of F.

As stated above, the coils G' and G² are 130

connected so as to neutralize the effect on the core G^3 , and as long as the flow through both branches of the circuit will be in equal proportions the electromagnet G will remain unaffected; but as soon as the resistance of one or the other of the air-gaps E or E' is increased the balance of the two circuits will be disturbed and the greater part of the current will flow through the coil G' or G^2 , and as this greater flow will enable this coil to energize the core G^3 the device G will be made operative. It is now supposed that, as is usually the case, the siphon A' , with its appended piece of mica B , rests at zero. In this position of the siphon both of the air-gaps are free and the piece of mica on the siphon is positioned in the center between the two air-gaps of the two contact pairs. The flow of the current F will be equal in both of the coils G' and G^2 and the device G will remain inoperative; but as soon as the transmitting operator sends an impulse over the line, effecting the receiving device A , the siphon A' , with its appended non-conducting piece B , will move either to the right or left, as the case may be, and the mica will be moved from its center position to a position between the adjustable contacts C and C' or C^2 and C^3 , and as the mica offers a greater resistance to the flow of an interrupted current than air the balance between the two air-gaps will be disturbed and hardly any of this current will flow through the air-gap having the mica interposed, and the greater part of the current will therefore flow over the air-gap free from the mica. The direct current will divide in the same proportion, and the device G will therefore come into operation, and as the message is symbolized only by positive or negative impulses actuating the receiving device A , so that the siphon is pulled either to right or left, it is obvious that such change of position will greatly change the resistance of one or the other of the air-gaps and the device G will respond to any of these changes.

In Letters Patent above referred to I have described a dot as to be designated by one impulse, the polarity not coming into consideration, and a dash as to be designated by two impulses in quick succession, each impulse of a polarity different from the other, and it is clear that in telegraphing with such impulses the receiving operator will through device G , if the same is a sounder or similar instrument, readily ascertain the nature of the transmitted characters and will therefore readily read the message by sound.

It is preferred that the circuit of the direct source shall be provided with an impedance to effectually bar the alternating current, and in the drawings I have shown this impedance as K , and it is also preferred that the circuit of the source H shall be provided with a capacity, such as a condenser, so as to effectually bar the direct current, and in the draw-

ings I have shown this capacity as the condenser L .

It is unnecessary for me to state again that the device A may be replaced by any of the well-known receiving devices or relays, and in such cases the means B , adapted to disturb the balance of the circuits, has to be connected to the movable part of such device no matter if the same consists of conducting tongues or otherwise.

It may be stated that it is possible to replace the non-conducting piece B by a conducting-piece, and in this case the resistance of the path for the spark would be decreased if the piece is interposed between one of the contact pairs; but I have found that such arrangement is not well adapted for practical purposes, as a spark having once found its path through a conducting-piece usually follows the same, and the movement of the siphon, as is well known, is too restricted for the purpose of extinguishing such spark.

I do not claim here the method of relaying without direct contact, as the same will form the subject-matter of another application.

Having now described my invention, what I claim as new, and desire to secure by Letters Patent, is—

1. In combination with a receiving device connected to the line of transmission, a local circuit embracing air-gap, a high-tension current traversing said local circuit and air-gap, a translating device in said local circuit, and means operatively connected to the movable part of said receiving device to vary the flow of said high-tension current through said air-gap in accordance with the impulses received.

2. In electric transmission, a device adapted to make record of the incoming impulses and adapted to disturb through its movement the balance of two air-paths made conducting through the flow of a high-tension current, in combination with a direct source of current and electromagnetic translating device operatively connected to said air-paths.

3. In electric transmission means to receive the incoming impulses, means to translate said impulses, said second means comprising a circuit including air-gaps and a source of high-tension current adapted to overbridge said air-gaps, and a second circuit including a source of direct current and translating device, said direct current adapted to make circuit through said air-gaps only when said air-gaps are made conducting through the flow of the first-named source of current, the means to receive adapted to vary the resistance of said air-gaps.

4. In electric transmission a receiving device in combination with means to translate the received impulses, said means embracing a circuit comprising a source of interrupted or alternating current and two air-gaps, a second circuit comprising a direct source of

current and electromagnetic device, said second circuit operatively related to said first circuit and said air-gaps.

5. In telegraphy, means to translate the incoming impulses, said means embracing a direct source of current, a circuit including electromagnetic device for said source, the circuit conductively broken through resistance-paths, said resistance-paths made conductive through the flow of a high-tension current, in combination with a receiving device connected to the line of transmission and adapted through its movement to vary the resistance of said paths.

15 6. In electric transmission an electromagnetic device provided with two coils connected to a source of unidirective current in a manner so as to oppose their respective magnetizing influence, two pairs of contacts, each 20 pair included in a circuit comprising the source of current and one of said coils, the contacts of each pair adjusted so as to present an air-gap between them, a source of alternating or interrupted current connected 25 with one terminal to one contact of each of said pairs, and with the other terminal to the other contact of each of said pairs, and means to vary the resistance of one or the other of the air-gaps as to flow of the alternating or interrupted current in accordance 30 with the received impulses.

7. In telegraphy, two pairs of adjustable contacts, a support for each of said pairs, one contact of each pair connected in multiple 35 arc to one side of a source of high-tension current and the other contact of each pair connected in multiple arc to the other side of said source of high-tension current, a source of direct current, an electromagnetic device 40 provided with two coils connected to said direct source so as to oppose their respective magnetizing influence, the source of current connected with one pole to one contact of each of said pair and connected with the 45 other pole to the junction of said two coils, the free terminal of one of said coils connected to one contact of one of said pairs, and the free terminal of the second of said coils connected to one contact of the second 50 of said pairs, each pair of contacts adjusted in a manner so as to form a path, non-conducting for a straight current, between same, in combination with means actuated by the incoming current to increase the resistance 55 of one or the other of said paths to the flow of the high-tension current in accordance with the received impulses.

8. In telegraphy, a siphon-recorder pro-

vided with means to record the incoming messages, a local circuit including a unidirective source of comparatively low potential and an alternating or induced current of comparatively high potential, a translating device, circuits in operative relation to both of said sources including paths non-conducting for said unidirective current but made conducting for said current through the passage of the high-tension current, and means operatively connected to the siphon-recorder to vary the resistance of one or the other of 70 said paths.

9. In a device of the class described, means to actuate a localized electromagnet, said means embracing a unidirective source of current, an electromagnet and electrically-interrupted circuit for same, a high-tension current producing a conducting-path between the interrupted parts of said circuit, and means coaxing with a receiving device to vary the resistance of the interrupted circuit.

10. Means to actuate a local electromagnet with the aid of a receiving device connected to the line of transmission without direct contact with the circuit of said local 85 magnet, said means embracing two circuits, one including a source of high-tension current and one including a source of unidirective low-tension current, the terminals of both circuits connected to conducting means 90 presenting between them a path non-conducting for the unidirective source but conducting for the high-tension source, an electromagnet, and means coaxing with the receiving instrument to vary the resistance of 95 said path.

11. Means to alter the resistance of a local circuit in accordance with the incoming telegraphic impulses, said means embracing a source of current of comparatively low potential, a circuit for same, parts of said circuit non-conductive to said source, a source of current of comparatively high potential reducing the resistance of said non-conductive parts and means responding to the incoming impulses to vary the flow of the high-potential current through the non-conductive parts in accordance with the incoming impulses.

In testimony whereof I hereby sign my name, in the presence of two subscribing witnesses, this 22d day of March, A. D. 1905.
